PLOW BOTTOM WITH DETACHABLE
PLOW POINT

Herbert N. Baker, Syracuse, N. Y., assignee to
Syracuse Chilled Plow Co., Inc., Syracuse, N. Y.,
a corporation of New York

Application October 25, 1944, Serial No. 560,268

12 Claims. (Cl. 97—124)

1

This invention relates generally to agricultural implements and more particularly to plows and other earth working tools.

The object and general nature of the present invention is the provision of certain new and useful improvements in plows of the type having a detachable and replaceable plow point, and it is also an important feature of this invention to provide a novel plow frog, a novel plow point, and a novel wing or share blade, all particularly constructed to facilitate attaching the same to complete the plow bottom and to improve the operating efficiency of the latter as a whole.

More specifically, it is a feature of this invention to provide a plow having improved clamping means for holding the plow point in position firmly and rigidly on the frog. In this connection, it is a further feature of this invention to provide improved clamping means of the wedge type which not only draws the point into proper position, generally longitudinally of the frog, but also forces the point generally laterally against the adjacent edge of the wing or blade and against the landside edge of the frog which portions of the point overlap.

These and other objects and advantages of the present invention will be apparent to those skilled in the art after a consideration of the following detailed description, taken in conjunction with the accompanying drawings.

In the drawings:

Figure 1 is a top or plan view of a plow bottom in which the principles of the present invention have been incorporated.

Figure 2 is a fragmentary enlarged bottom view.

Figure 3 is a perspective view of the underside of the plow point and the adjacent portions of the wing or share blade.

Figures 4 and 5 are sectional views taken, respectively, along the lines 4—4 and 5—5 of Figure 2.

Referring now to the drawings, more particularly to Figures 1 and 2, the plow bottom which I have chosen to illustrate the present invention is indicated in Figure 1 in its entirety by the reference numeral 1 and comprises a frog 2 which generally serves as the supporting means for the other parts, a moldboard 3, bolted, as at 4, to the moldboard-receiving plate 5 of the frog 2. For purposes of clarity the moldboard has been omitted in Figure 2. The frog 2 also includes a landside plate 6 welded to the plate 5 a short distance laterally inwardly of the landside edge 7 of the moldboard plate 5 so as to

2

provide a flange or overhanging construction with which the point, to be described below, particularly cooperates. A brace 9 is fixed, as by welding, to the landside plate 6 and to the moldboard-receiving plate 5, and the intermediate portion of the brace 9 is provided with a section that is apertured to receive the rear portion of a clamping bolt 12, to which detailed reference will be made below.

10 The plow bottom 1 also includes a wing or share blade 16 that is bolted, as at 17, to the lower forward portion of the frog, particularly the moldboard-receiving plate 5 thereof, the wing or blade 16, in effect, forming a continuation of the upper surface of the moldboard 3. The wing or blade 16 includes a landside edge 19 which is spaced laterally from the landside face or edge of the moldboard and generally in a furrowward direction from the plane of the landside 21 of the plow. The landside 21 is bolted to the lower rear portion of the landside plate 6 of the frog.

15 A separate detachable and replaceable plow point 25 is fixed to the forwardmost portion of the frog 2 and, as best shown in Figure 3, comprises a flat main body section 26 having a thicker forward portion 27 and a point or soil entering end 28. The plow point 25 also is provided with a flange 31 disposed in a plane generally parallel to the landside plate 6, when the point is attached to the plow. The plane of the main body section 26 of the point 25 makes an acute angle with respect to the plane of the plow point landside flange 31. The latter is provided with a pair of lugs 33 spaced below (above in Figure 3) 20 the face of the rear portion of the plow point, the spacing being such that the landside edge 7 of the frog may be received therebetween. Between the sections 26 and 27 of the point 25 there is an abutment shoulder 34 which lies in 25 a line making an acute angle with respect to the plane of the landside flange 31. The abutment edge 34 is adapted to engage the landside portion 35 of the forward edge 36 of the frog. The wing 16 has a similar rearwardly facing shoulder 38 which, when the wing is secured in place to the frog, engages the forward edge 36 of the frog furrowwardly of the point 25. As best shown in Figure 2, the two abutment shoulders 34 and 38 are normally in alignment.

30 As best shown in Figure 3, the under side of the plow point 25, adjacent the rear and furrowward edges, has a lug 41 having an undercut surface 42. This lug is adapted, when the point 25 is mounted in position on the frog, to extend through an opening 43 in the forward portion of

the moldboard-receiving plate 5 of the frog 2, the opening 43 being disposed fairly close to the landside plate 6 of the frog. Cooperating with the lug 41 is a clamping bolt lug 44 having an undercut surface 45 and a pair of opposite shoulders 46 and 47. The portion 48 of the lug 45 that carries the undercut surface 44 fits snugly into the opening 43 in the frog, and the shoulders 46 and 47 which are approximately in vertical alignment with the inclined clamping surface 45, engage the under surface of the frog at opposite sides of the opening 43. The lug 44 is secured in any suitable manner to the forward end of the clamping bolt 12, the rear end of which is threaded and receives one or more nuts 49 which, reacting against the brace 9, serves to hold the point 25 in position. From Figures 4 and 5 it will be noted that the undercut surface 45 of the lug 44 engages the undercut surface 42 on the lug 41, the latter being carried by the point 25 so that when the nuts 49 are tightened, there is a component of force acting to hold the point 25 down against the upper face of the frog, the shoulders 46 and 47 bearing against the lower face of the frog at opposite sides of the opening 43. It will be noted that the bolt 12 is arranged at an angle to the plane of the landside plate 6 so that the pull exerted by the bolt on the point 25 has a certain amount of laterally directed force component acting to hold the point 25 snugly against the landward edge 7 of the frog. Thus, the lugs 33 are held fully engaged over the landward edge 7. Furthermore, since the abutment shoulder 34 on the point 25 is at an angle to the landside flange 31, when the bolt 12 is tightened the shoulder is pulled against the forward edge 35 of the frog. This serves further to cause the point 25 to be drawn laterally inwardly as well as rearwardly relative to the frog. Thus, the point 25 is securely held in position by what amounts to substantially a direct pull by the clamping bolt 12, the lug 44 thereof reacting against the frog for holding the point down against the upper face of the frog and, at the same time, holding the point 25 in its laterally biased position with the lugs 33 engaged over the landside edge of the frog. As best shown in Figure 3, the furrowward edge of the point 25 is beveled, as at 51, and overhangs the beveled end 19 of the blade 16, and the bolt 12 when tightened securely holds these edges together. Preferably, the landward corner 52 of the wing lies behind an extension 53 of the plow point 25, and the shoulder 33 on the wing 16, bearing against the forward edge of the frog, serves to prevent the wing 16 from being forced rearwardly out of position.

In order to protect the lug 44 and associated parts, a sole plate 55 is welded or otherwise secured to the forward portion of the landside plate 6 and the lower edge of the moldboard-receiving plate 5, preferably along the edge section 35. This sole plate also reinforces the frog parts.

While I have shown and described above the preferred structure in which the principles of the present invention have been incorporated, it is to be understood that my invention is not to be limited to the particular details shown and described above, but that, in fact, widely different means may be employed in the practice of the broader aspects of my invention.

What I claim, therefore, and desire to secure by Letters Patent is:

1. In a plow, a frog having an upper point receiving face and an opening therethrough, a de-

- tachable point engageable with said face and having a lug extending through said opening, said lug having an undercut edge, and a fastening member having a pair of spaced apart shoulders adapted to engage the underside of said frog at opposite sides of said opening and a lug having an undercut edge adapted to extend into said opening and engage the undercut edge of the lug on said point, for holding the latter in place against the upper face of said frog.
2. A plow bottom comprising a frog, a point adapted to be mounted on the upper face of said frog with a portion disposed against the landside face of the frog, a drawbolt mounted on the frog 15 on the lower face thereof, cooperating wedge lugs carried by said drawbolt and on the lower face of said point, said lugs having cooperating undercut surfaces, whereby tightening the drawbolt serves to hold the point down against the upper 20 face of said frog, and means separate from said wedge lugs and carried by said frog and point for drawing the point laterally against the landside face of the frog when the drawbolt is tightened.
- 25 3. In a plow bottom, a frog having a projecting toe portion provided with a landside edge, a detachable point adapted to fit against the upper side of said projecting toe portion and having a landside flange with a portion extending beneath 30 said toe portion of the frog, means connected between the frog and said point for drawing the latter onto the frog in a generally longitudinal direction, and cooperating surfaces carried, respectively, by said frog and point and angled so 35 that when the point is drawn onto the frog in a generally longitudinal direction, the point is also urged generally laterally so as to engage the landside flange of the plow point against the landside edge of said frog.
- 40 4. In a plow bottom, a frog having a landside edge, a landside plate which said landside edge overhangs, and a forward edge disposed at an acute angle to the plane of said landside plate, a detachable point adapted to overlie the forward 45 upper portion of said frog and having a landside flange formed to engage said landside edge of said frog and a generally rearwardly facing shoulder adapted to engage against the landward portion of the forward edge of said frog, a wing 50 adapted to be secured to said frog and having a beveled edge spaced from the landside edge of the frog and a rearwardly facing shoulder adapted to engage the forward edge of said frog forwardwardly of said point, the latter having a beveled edge adapted to overlie the beveled edge of said wing, and means connected between the frog and said point for drawing the latter onto said frog so as to hold the landside flange of said point against the landside edge of said frog and 55 also holding the rearwardly facing shoulder of said point against the forward edge of said frog with the beveled edge of said point overlying the beveled edge of said wing.
5. The invention set forth in claim 4, further 60 characterized by said forward edge of the frog being generally straight and the shoulder on said point and the shoulder on said wing being generally in alignment when the wing and point are fixed to said frog.
6. As an article of manufacture, a plow frog 70 comprising a moldboard-receiving plate, a landside-receiving plate fixed to said first plate adjacent but spaced from the landside edge thereof, thereby providing an overhanging point-receiving flange, a lug-receiving opening in said first

plate adjacent said second plate but spaced on the side thereof opposite said flange, and a sole plate fixed to the lower edges, respectively, of said moldboard- and landside-receiving plates and substantially under said lug-receiving opening.

7. In a plow, a frog having an upper point receiving face and an opening therethrough, a detachable point engageable with said face and having a lug extending through said opening, said lug having an undercut edge, and a fastening member having means engageable with the underside of said frog at opposite sides of said opening and a lug having an undercut edge adapted to extend into said opening and engage the undercut edge of the lug on said point, for holding the latter in place against the upper face of said frog.

8. As an article of manufacture, a plow frog comprising a moldboard-receiving section, a landside-receiving plate fixed to said first plate adjacent the landside edge thereof, a lug-receiving opening in said first section adjacent said second section, and a sole plate fixed to the lower edges, respectively, of said moldboard- and landside-receiving section and substantially under said lug-receiving opening.

9. As an article of manufacture, a plow frog having a pair of angularly related sections, one at the landside side and the other extending generally downwardly and laterally away from said one section, and a sole plate fixed to the lower portions of said frog sections.

10. In a plow, a frog having an upper point receiving face and an opening therethrough, a detachable point engageable with said face and having a lug extending through said opening, said lug having an undercut edge, and a fastening member having abutment means adapted to engage the underside of the frog adjacent said opening and a lug having an undercut edge adapted to extend into said opening and engage the undercut edge of the lug on said point, for holding the latter in place against the upper face of said frog.

11. In a plow, a frog having a landside edge and a forward edge disposed at an acute angle to the plane of said landside edge, a detachable

point adapted to overlie the forward upper portion of said frog and having a landside flange formed to engage said landside edge of said frog and a generally rearwardly facing shoulder adapted to engage against the landside portion of the forward edge of said frog, a wing adapted to be secured to said frog and having a beveled edge spaced from the landside edge of the frog and a rearwardly facing shoulder adapted to engage the forward edge of said frog furrowward of said point, the latter having a beveled edge adapted to overlie the beveled edge of said wing, and means connected between the frog and said point for drawing the latter onto said frog so as to hold the landside flange of said point against the landside edge of said frog and also holding the rearwardly facing shoulder of said point against the forward edge of said frog with the beveled edge of said point overlying the beveled edge of said wing.

12. A plow bottom comprising a frog, a point adapted to be mounted on the upper face of said frog with a portion disposed against the landside face of the frog, a drawbolt mounted on the frog on the lower face thereof, cooperating contacting abutment portions on said point and forward edge of the frog and angled whereby rearward movement of said point relative to the frog serves to cause said portion of the point to be forced laterally against the landside face of the frog, said contacting portions extending substantially the width of said point, and means mounting the drawbolt on the frog in a position such that the line of force exerted, when the drawbolt is tightened, extends at an angle to the general plane of the landside face of the frog and intersects said contacting abutment portions at a point adjacent said plane.
